UNITED STATES PATENT OFFICE.

CHARLES J. ADDY, OF MALDEN, MASSACHUSETTS.

HEEL-BEADING MACHINE.

SPECIFICATION forming part of Letters Patent No. 268,593, dated December 5, 1882.

Application filed October 20, 1882. (Model.)

To all whom it may concern:

Be it known that I, CHARLES J. ADDY, of Malden, county of Middlesex, State of Massachusetts, have invented an Improvement in Heel-Beading Machines, of which the following description, in connection with the accompanying drawings, is a specification, like letters on the drawings representing like parts.

This invention has for its object the production of an automatic machine for beading the heel-seat and top lift of a boot or shoe heel. This class of work has usually been done by a tool held directly in the hand of the operator; but in the machine devised by me for this purpose the beading-tool, provided with surfaces properly shaped to bead both the top lift and the heel-seat, is connected with a lever, which is vibrated rapidly by a crank-pin on a rotating shaft. The shoe the heel of which is being beaded is shown as held on a movable rest.

Figure 1 represents in front view a heel-beading machine embodying my invention; Fig. 2, a top or plan view, with the heel of a shoe in position to have its heel-seat beaded; and Fig. 3, a sufficient portion of the top of the machine to show the heel in position to have the top lift beaded.

The part A supports an arm, A', having bearings b b for a shaft, c, having at its front end a disk, provided with a crank-pin, c', which enters a slot or groove in a lever, d, pivoted at d' on a bracket, d'', of arm A'. The outer or free end of the lever d has attached to it by screw 2 the beading-tool e. This beading-tool has a projecting lip or top-lift beader, 3, and a projecting lip or heel-seat beader, 4, the former to operate against the top lift, as in Fig. 3, and the latter against the heel-seat, as in Fig. 2,

each lip producing its own bead. When the beader 3 is operating to bead the top lift the 40 end of the top lift bears against the flat face 6 of the tool between the beaders 3 and 4, as in Fig. 3, the said face 6 serving as a rest for the heel-seat, and also serving to finish the top lift upon its under face at its edge. The shaft 45 e will be driven rapidly by a belt on the pulley g. (Shown only in Fig. 2)

The shoe h, having the heel h' to be beaded, is placed upon a shoe-support, composed of a horizontally-sliding rod, m, having a head, m², 50 to enter the shoe and bear against the inner sole. This rod m is extended through a swivel, m³, having a pin, m⁴, entered loosely into the upright or post n, so that the said rod m, with the shoe upon it, may be turned or moved in 55 desired direction with relation to the post n.

I claim—

1. The lever d and means to move it, combined with the beading-tool e, having the two beaders 3 4, with a surface, 6, between them, 60 to operate substantially as described.

2. The lever d, rotating shaft e, crank-pin to move it, and attached beading-tool, and the beaders 3 4, the former to bead the top lift and the latter to bead the heel-seat, combined with 65 a movable shoe-support to hold the shoe and enable the heel to be properly presented to the action of the two beaders, substantially as described.

In testimony whereof I have signed my name 70 to this specification in the presence of two subscribing witnesses.

CHARLES J. ADDY.

Witnesses:

G. W. GREGORY,
B. J. NOYES.
